DESIGN FOR A DOLL

Arthur D. Norcross, New York, N. Y., assignor to Norcross, New York, N. Y., a partnership composed of Arthur D. Norcross and June Norcross Webster

Application February 4, 1938, Serial No. 74,885

Term of patent 7 years

To all whom it may concern:

Be it known that I, Arthur D. Norcross, a citizen of the United States, residing in the city, county, and State of New York, have invented a new, original, and ornamental Design for a Doll, of which the following is a specification, reference being made to the accompanying drawing forming a part thereof, in which:

I claim:

The ornamental design for a doll, as shown.

ARTHUR D. NORCROSS.
